MULTIPLE HYDROCYCLONES

Freerk J. Fontein, Heerlen, and Jan N. J. Leeman,
 Hoensbroek, Netherlands, assignors to Stamicarbon N. V., Heerlen, Netherlands

Application June 14, 1950, Serial No. 168,132

14 Claims. (Cl. 209—211)

1

This invention relates to hydrocyclones such as are used to treat solids in liquid suspension for the purpose of thickening or of classifying the suspended solids into predetermined fractions. Such solids may be either organic or inorganic, such as starch, paper-pulp, ores, coal, phosphate rock, and the like. However, such diverse materials require different dimensions of hydrocyclones and different operating conditions, so a brief description of the general characteristics of such a hydrocyclone may be helpful.

A hydrocyclone is a generally cylindrical vessel comprising a truly cylindrical part or section which merges into a generally conical part or section. There is an opening at the apex of the cone of the conical section and there is another opening, coaxial with the apex opening, in the cover-plate on the cylindrical section.

In the opening in the cover-plate, is carried a tube that extends from that plate outward and extends inwardly into the cylindrical section of the hydrocyclone. This is called a vortex finder. There is a tangential feed inlet to the cylindrical section.

In operation, the liquid suspension is supplied to the hydrocyclone under pressure through the tangential feed inlet to the cylindrical section whereby the suspension is given a quick enough rotational impulse to keep it rotating during its passage through the hydrocyclone. One fraction of the suspended solids is discharged from the hydrocyclone through the apex opening while another fraction is discharged through the vortex finder and thus from the base of the generally conical hydrocyclone. The apex-discharge contains the larger suspended solids while the base-discharge contains the smaller suspended solids, if separation is being based upon size difference. If separation is based upon specific gravity difference, the solids having less specific gravity are discharged through the base, while the solids having greater specific gravity are discharged through the apex. As separation in a hydrocyclone is dependent upon intense rotational forces, no obstructions can be tolerated in the hydrocyclone which must have a perfectly smooth bore for otherwise harmful secondary eddies are set up. The feed entrance also must be smooth and unobstructed.

The functioning of a hydrocyclone is readily effected by slight environmental changes, such as changing the area of the infeed entrance; the infeed pressure; the diameter of the apex-discharge; the diameter of the length of the vortex finder; the diameter of the length of the cylind-

2

rical section; or the shape of the conical section. In general, the smaller the dimension of the suspended solids to be separated, the smaller must be the diameter of the cylindrical section of the hydrocyclone. For instance, a hydrocyclone for the separation of phosphate rock from limestone will have a cylindrical section of the order of 48 inches in diameter, whereas a hydrocyclone for the thickening of starch will have a cylindrical section of the order of one-half an inch in diameter. A 48-inch hydrocyclone will have an hourly capacity of about 10,000 times that of a half-inch hydrocyclone—the capacity of the latter being about 25 gallons per hour.

5 Thus, in a starch factory where it is desired to thicken say 25,000 gallons of starch per hour, 1,000 half-inch hydrocyclones would be required. While this may seem to be a startling number, the efficiency of these smaller 10 hydrocyclones for making satisfactory separations along the line of infinitesimal size differences, is such as to make their use desirable. However, mechanical problems of hooking up so many tiny hydrocyclones as to feed, and discharge, are serious. So it is a major object of 15 this invention to take this tiny type of hydrocyclone out of the laboratory stage by devising ways and means whereby they are to be supplied and discharged economically without having a 20 maze of feed and discharge pipes and fittings.

25 A further object of this invention is to devise ways and means to collect a considerable number of hydrocyclones in a small space. Another object of the invention is to devise ways and means 30 whereby a multiplicity of hydrocyclones, herein-after referred to as a multiple-hydrocyclone, can be cast or moulded into a unit which can be housed in a single casing or container.

35 A more specific object of the invention is to 40 cast or mould the conical and cylindrical section and the infeed entrance thereinto of every hydrocyclone in the multiple-hydrocyclone into a block-like body unit, while casting or moulding separate cover-plates provided with vortex-finders to cover the hydrocyclones of the multiple-hydrocyclone. Another object of the invention 45 is to devise ways and means to exert forces from every direction on a multiple-hydrocyclone in operation, so that such multiple-hydrocyclone 50 even when it is composed of resilient material like soft rubber, will retain its original shape in operation.

55 In other words it is an object of this invention to secure together a soft rubber body block and a multiplicity of cover-plates in a main body as-

sembly to which can be applied a minimum of other separable sections that contain within themselves the essential feed and discharge openings required to make the multiple-hydrocyclone into an operable device with no external accessories other than a unitary feed conduit and a unitary conduit each for the base-discharges and for the apex-discharges. A further object of the invention is to devise ways and means whereby the discharge of one multiple-hydrocyclone can be fed into and treated in another multiple-hydrocyclone which is housed in an extension of the casing housing the first mentioned multiple-hydrocyclone.

To realize these objects, the invention comprises a construction consisting of a substantially cylindrical body block, cover-plates and a casing to secure these parts together, this construction containing at least as many hydrocyclones as there are cover-plates in the construction, an infeed entrance for every hydrocyclone and a substantially central hole connected directly or indirectly with the infeed entrances. The central hole is connected with an infeed tube. The vortex-finders of the hydrocyclones of a multiple-hydrocyclone discharge into one common vessel, whereas the apex-apertures discharge into another common vessel. The construction is provided with means to disconnect the infeed means and the separate discharge means of one multiple-hydrocyclone, although a discharge vessel of one multiple-hydrocyclone may be connected with the central hole of another multiple-hydrocyclone.

The best embodiment of the invention now known to us will be described hereinafter for illustrative purposes but it is to be understood that it is illustrative and not limiting because obviously certain changes and modifications are possible as long as they fall within the metes and bounds as defined by the appended claims or the equivalents of the latter's requirements.

In the accompanying drawings the embodiment has been illustrated wherein:

Figure 1 is a perspective view of a multiple-hydrocyclone partially provided with cover-plates and partially broken away;

Figure 2 is a longitudinal section of the multiple-hydrocyclone;

Figure 3 is a cross-section of the multiple-hydrocyclone;

Figure 4 is a plan view of the multiple-hydrocyclone partially provided with cover-plates;

Figure 5 is a longitudinal section of an assembly with two multiple-hydrocyclones in series;

Figure 6 is a plan view of the assembly of Figure 5;

Figure 7 is a longitudinal section of an assembly with two multiple-hydrocyclones in parallel.

The cylindrical body block or multiple-hydrocyclone 1 is shown in the Figures 1 to 4 inclusive. A central cylindrical infeed hole 2 extends from one end to the other end of block 1 so that the block 1 has an annular shape. Three radial holes or ducts 3 connect the central hole 2 with the periphery of the block. The block 1 is provided with a number of bores or hydrocyclones 4 whose axes are arranged on two cylinders coaxial with cylindrical block 1. The bores are of diminishing diameter and extend from one end to the other end of block 1, the narrow ends of the bores pointing in the same direction. All hydrocyclones 4 have the same dimensions and

one infeed entrance 5 debouching tangentially thereto. All the infeed entrances 5 are situated in one plane perpendicular to the axis of the cylindrical block 1. The infeed entrances of the outer hydrocyclone are connected with the periphery of block 1 whereas the infeed entrances of the inner bores are connected with the central hole 2. Every hydrocyclone 4 consists of a cylindrical part 6 into which the infeed entrance 5 debouches, a conical part 7 and a cylindrical discharge aperture or apex opening 8. The cover-plates 9 cover the bores 4 and the infeed entrances 5, so as to form the base of the hydrocyclones. In the drawings only a few cover-plates 9 are shown so that the features of the body block 1 are visible, but it is obvious that every bore 4 and every infeed entrance 5 has to be covered when the multiple hydrocyclone is operated.

The cover-plates 9 are provided with tubes or vortex-finders 10 co-axial with the bores 4 they cover and extending into the bores and in the opposite direction. To hold the vortex-finders 10 in the centres of the hydrocyclones 4 the body block 1 is provided with an extension 11 wherein spaces are left which fit around the cover-plates 9, preventing them to move sideways. The block is further provided with a resilient outer collar or flange 12 and a resilient inner collar or flange 13 both connected with the apex end of block 1, the loose-end of the outer collar 12 encircling the block and the loose end of the inner collar 13 being situated within the central hole 2.

Figures 5 and 6 show an assembly with two soft rubber multiple-hydrocyclones in series. The casing 14 comprises an outer tube 15 which surrounds multiple-hydrocyclone 1, while fitting closely around the outer collar 12 of the block. The inner tube 16 fits closely in the inner collar 13 of the multiple-hydrocyclone. Cover 17 is a circular member provided with circular perforations 18 surrounding the vortex-finders 10. Bottom 19 is a circular plate provided with a central perforation 20 surrounding inner tube 16 and with circular perforation 21 facing the apex apertures 8 of multiple-hydrocyclone 1. The outer tube 15 and the inner tube 16 are connected by wall 22 opposite bottom 19. Between wall 22 and bottom 19 there is a discharge opening 23 leading to tube 24 and valve 25. Wall 22 is provided with an infeed connection 26 for inner tube 16. The outer tube 15 is provided with a flange 27 perforated for receiving the bolts 28 which can be tightened by nuts 29. The cover 17 has a cylindrical part 30 and a flange 31, so that the cover 17 can be brought into the outer tube 15 with flange 31 resting on flange 27, tightening the cover-plates 9 against the block 1 in the meantime. The opposite side of flange 31 meets casing 32, which is similar to casing 14 but which has no part corresponding with infeed connection 26. Number 33 refers to an outer tube, 34 to an inner tube, 35 to a cover with perforations 36, 37 to a bottom with a central perforation or aperture 38 and circular perforations 39, 40 to a well, 41 to a discharge opening leading to tube 42 and valve 43, 44 to a perforated flange of outer tube 33, 45 to the cylindrical part of cover 35 and 46 to the flange of cover 35. On top of flange 46 is a closing member 47 perforated for receiving the bolts 28 and a discharge aperture 48 leading to tube 49 and valve 50. Inside casing 32 is multiple-hydrocyclone 51, similar to multiple-hydrocyclone 1 and showing the same features. Packing 52 is provided between the flanges 27 and

31, between 31 and 32, between 44 and 46 and between 46 and 47 to prevent leakage. By tightening the five nuts 29 all separate parts of the multiple-hydrocyclone and the casing are clamped together.

In operation the material to be treated, e. g. a starch suspension, is introduced continuously under pressure into the inner tube 16 and enters central hole 2 of multiple-hydrocyclone 1. The pressure of the suspension presses the loose end of collar 13 against the outer surface of inner tube 16 so that no suspension can leak out. Part of the suspension passes through the radial holes 3 and enters the space between block 1 and the inner surface of tube 15. The pressure of the suspension forces the loose end of collar 12 against the inner surface of outer tube 15 so that no suspension can leak out. The suspension therefore is led through the infeed entrances 5 into the bores of hydrocyclones 4. The inner hydrocyclones receive suspension from central hole 2 directly, whereas the outer hydrocyclones receive suspension from the space between the block 1, and the outer tube 15. Rotating bodies of suspension come into being in the cylindrical parts 6 and conical parts 7 of the hydrocyclones 4 and the separated fractions are discharged through the apex openings 8 and through the vortex-finders 10. The apex-discharge of the multiple-hydrocyclone is received in a space confined by wall 22, bottom 19, inner tube 16 and outer tube 15 and is discharged therefrom through discharge opening 23, tube 24 and valve 25. The vortex-finder-discharge is received in a space confined by cover 17 and wall 40 and closed by packing 52 and enters through inner tube 34 into the central hole 2 of multiple-hydrocyclone 51. The operation of multiple-hydrocyclone 51 corresponds with the operation of multiple-hydrocyclone 1. The apex-discharge of multiple-hydrocyclone 51, i. e. the second apex discharge, is received in a space confined by wall 40, bottom 37, inner tube 34 and outer tube 33 and is discharged therefrom through discharge 41, tube 42 and valve 43. The vortex-finder-discharge of multiple-hydrocyclone 51 is received in a space confined by closing member 47 and cover 35 and closed by packing 52 and is discharged through aperture 48, tube 49 and valve 50.

The operation of the multiple-hydrocyclones 1 and 51 can be controlled by adjusting the valves 25, 43 and 50 and by regulating the infeed pressure in inner tube 16.

The assembly shown in Figures 5 and 6 contains two multiple-hydrocyclones of twenty-four hydrocyclones each, yet only four outer pipe connections are required. The suspension exerts pressure on the blocks from all sides and the blocks therefore are only slightly deformed, even if they consist of an easily deformed material.

The separate hydrocyclones thus retain their circular shape. This makes it possible to cast or mould the multiple-hydrocyclones of soft rubber, which is of great advantage because soft rubber is wear resistant and has a smooth surface and is therefore especially suited for the inner surface of small hydrocyclones.

The same units as described in Figures 5 and 6 may be used to assemble three multiple-hydrocyclones in series, so that every casing contains 72 hydrocyclones. Such an assembly is especially useful for the thickening of starch suspensions.

A similar assembly with two multiple-hydrocyclones in parallel is shown in Figure 7. The suspension is introduced through tube 53 into a space surrounded by cylindrical member 54 and

is divided into two parts, both parts passing into an inner tube 55. The assembly further comprises casings 56, outer tubes 57, inner tubes 55, covers 58 with perforations 59, bottoms 60 with central perforation 61 and circular perforation 62, walls 63, discharge openings 64 leading to tubes 65 and valves 66, perforated flanges 67 of outer tubes 57, cylindrical parts 68 and flanges 69 of covers 58, closing members 70, perforated for receiving the bolts 71 which can be tightened with nuts 72, discharge apertures 73 leading to tubes 74. Packing 75 is provided between parts of the casing to prevent leakage. Inside the casings 56 are multiple-hydrocyclones 76 similar to multiple-hydrocyclone 1.

The assembly as shown in Figure 7 contains 48 hydrocyclones, yet only 5 pipe connections are required. In a factory requiring one thousand small hydrocyclones only 21 apparatus as shown in Figure 7 have to be installed.

We claim:

1. Apparatus for a multiple-hydrocyclone comprising a cylindrical block with a cylindrical hole centrally therethrough and radial holes connecting the central hole with the periphery of the block, bores of diminishing diameter from one end to the other end each bore having at its large end an infeed entrance tangentially debouching thereinto, the axes of the bores being arranged on two cylinders co-axial with the block, the infeed entrances of the bores of the inner cylinder being connected with the central hole, the infeed entrances of the bores of the outer cylinder being connected with the periphery of the block, a cover-plate for each bore and the infeed entrance thereto with each cover-plate having a co-axial aperture therethrough for each bore and a tubular member extending axially from the cover plate into the bore and in the opposite direction, an outer and an inner resilient collar connected with the block at the edge where the bores have their smaller ends, the loose end of the outer collar surrounding the block, the loose end of the inner collar lying within the central hole, all bores with the infeed entrances debouching thereinto and the apertures leading therefrom defining identical hydrocyclones and means for enclosing the block having a casing encircling the block and a cover plate as well as a bottom plate with an infeed tube wherein the outer collar closely co-acts with the casing and the inner collar closely co-acts with the feed tube.

2. A casing for apparatus according to claim 1 comprising an outer tube whose inner diameter is larger than the outer diameter of the cylindrical block but smaller than the largest diameter of the resilient outer collar therearound so that said collar closes the opening between the multiple-hydrocyclone and the outer tube, an infeed tube whose outer diameter is smaller than the inner diameter of the central hole of the multiple-hydrocyclone but larger than the smallest diameter of the inner resilient collar therein so that said inner collar provides a closed connection between the infeed tube and the multiple-hydrocyclone, a cover with apertures arranged as to correspond with the discharge apertures of the hydrocyclones to cover the end of the multiple-hydrocyclone at the end opposite its collars, a bottom with apertures arranged as to correspond with the infeed tube and with the discharge apertures of the hydrocyclones to cover the collared end of the multiple-hydrocyclone and means to clamp the outer tube, the infeed tube,

the cover and the bottom together so that the multiple-hydrocyclone is tightened between the cover and the bottom.

3. A casing according to claim 2 with the addition of a closed vessel into which the apertures of the cover debouch and having a discharge opening.

4. A casing according to claim 2 provided with a closed vessel having a discharge opening with the apex apertures of the hydrocyclones debouching through the bottom into the vessel.

5. A casing according to claim 4, wherein the discharge opening has regulating means.

6. A multiple-hydrocyclone comprising a cylindrical block having an axial hole therethrough and therearound a plurality of axially disposed cylindrical bores large at one end and of diminishing diameter at the other smaller end, cover means for the large ends having an aperture therethrough for each, an apertured bottom plate closing an end of the block whose apertures form an outlet area therethrough for liquid discharging from the smaller end of the bores, an apertured top plate for the other end of the block whose apertures form an outlet area therethrough for liquid discharging from the large end of each bore, clamping means connecting the top plate and the bottom plate, conduit means for carrying away liquid discharging through the bottom plate, conduit means for carrying away liquid discharging through the top plate, means for feeding a suspension to be treated by the hydrocyclone into the central hole as a receiver of a common supply of feed, and means for distributing feed from the hole to the bores having an individual feed-conducting passageway leading from the common feed supply and debouching tangentially into the large end of each bore.

7. A multiple-hydrocyclone according to claim 6, with the addition of a casing encircling the block at its side but constructed and arranged to leave a liquid holding space between it and the block, a further plurality of bores and associated cover plates in all respects like the first plurality thereof except that their feed entrance passageways connect each of them with said space, and liquid-conducting conduit means connecting the hole with said space.

8. A multiple hydrocyclone according to claim 6, wherein the suspension feeding means include tubular means projecting through the bottom plate, with the addition of resiliently deformable liquid-sealing means between the tubular means and the block.

9. A multiple hydrocyclone comprising a block with a central axial hole and parallel to that hole a plurality of substantially conical bores of diminishing diameter with all the base outlets at one end of the block and all the apex outlets at the other end of the block, apertured top cover means for closing the base outlets of the bores except for an aperture aligned therewith, apertured bottom cover means having an aperture area to form an outlet for liquid discharging therefrom, pressure means including a tube for feeding a suspension to be treated in the hydrocyclone into the central hole, and a feed-conducting passageway tangentially debouching into the large end of each bore leading from the feed-receiving hole whose common feed supply is thus flowed through the feed passageways and distributed individually to the bores.

10. A multiple hydrocyclone according to claim 9, with the addition of a chamber for collecting discharge from the base outlets of the bores and

discharging it after being so collected, and of a chamber for collecting discharge from the apex outlets of the bores and discharging it after being so collected.

5. 11. A multiple hydrocyclone according to claim 10, wherein the tube for conducting the incoming feed passes through the chamber that collects discharge from the apex outlets.

12. A multiple hydrocyclone according to claim 10, wherein there are two such complete assemblies arranged in superposed position with the outlet from the casing that collects discharge from one set of similar outlets of the subjacent assembly comprising the tube that feeds to the central hole of the superjacent assembly.

13. A multiple hydrocyclone having a generally cylindrical casing with apertured cover means and an apertured bottom, an annular block with a feed-receiving central hole located co-axially within the casing having an inner and an outer ring of similarly directed substantially conical bores therethrough each of which bores is a hydrocyclone with a base outlet discharging through an aperture in the cover means, as well

25 as an apex outlet discharging through an aperture in the bottom, outwardly extending liquid-sealing means extending between the block and its casing at an elevation between said outlets to provide there a feed-receiving annular space

30 between the block and its casing above the sealing means, inwardly extending liquid-sealing means extending from the block into its hole at a similar elevation, feed-conducting ducts extending through the block from its hole to the annular space, an infeed entrance to each of the bores of the inner ring leading from the hole, an infeed entrance to each of the bores of the outer ring leading from said space, and a tube

35 projecting contactingly past the inwardly extending liquid-sealing means into the hole for conducting incoming feed thereto for distribution to each feed entrance of the bores of the inner ring thereof directly from the hole and to each feed entrance of the outer ring thereof indirectly from the hole through the radial ducts and said 45 annular space.

14. A multiple hydrocyclone having a casing with an apertured cover and an apertured bottom, a block with a feed-receiving central hole located within the casing having an inner and an outer ring of similarly directed substantially conical bores therethrough each of which bores is a hydrocyclone with a base outlet discharging through an aperture in the cover as well as an apex outlet discharging through an aperture in

50 the bottom, the block being spaced from its casing for a portion of its length above the apex outlets to provide there an annular feed-receiving space, feed-conducting duct means extending through the block from its central hole to the annular space, an infeed entrance to each of the bores of the inner ring leading from the central hole, an infeed entrance to each of the bores of the outer ring leading from the annular space, and a tube projecting sealingly into the central

55 hole for conducting incoming feed thereto for distribution to each feed entrance of the inner ring of bores directly from the hole and to each feed entrance of the outer ring of bores indirectly from the hole through the duct means and the 60 annular space.
